PUMPING APPARATUS

Lewis Tyree, Jr., 9955 S. Hamilton Ave., Chicago, Ill.
Filed Mar. 6, 1963, Ser. No. 263,260
4 Claims. (Cl. 103—5)

This invention relates to apparatus for pumping cryogenic liquids and more particularly to rotary positive displacement pumps for pumping such liquids.

The handling of cryogenic liquids (e.g. oxygen, nitrogen, etc.) having a boiling point which is lower than ambient temperature has presented a variety of difficulties which have heretofore not been completely resolved. One prime example of a situation wherein such difficulties are incurred is the pumping of a cryogenic liquid from a low pressure container to a high pressure storage tank or pipe line. This is true since the cryogenic liquids, which are usually and most desirably handled in a nearly natural boiling condition, are normally absorbing heat from the surrounding environment before and during pumping, and heat is absorbed by the liquid as work is being done by the pump. When so heated cryogenic liquids tend to first come to their boiling point and then undergo a phase transition to a gas or vapor state (i.e. "flash"). Not only is this "flashing" undesirable since it leads to vapor locking or failure of the pumping system but it also prevents the accurate metering of the liquid being delivered to the high pressure storage tank. Attempts to resolve this heat absorbing difficulty and to preclude "flashing" which results therefrom have centered about the use of auxiliary refrigerating or sub-cooling means that substantially increases the cost or complexity of the pumping system.

It is the prime object of the present invention to provide an improved apparatus for pumping cryogenic liquids.

A further object of the present invention is to provide a rotary positive displacement pumping apparatus for handling cryogenic liquids while minimizing the possibility of vapor lock.

A further object of the present invention is to provide an essentially vapor lock-free rotary positive displacement pump for handling cryogenic fluids which does not require auxiliary refrigerating or sub-cooling means.

Still another object of the present invention resides in the provision of an improved rotary positive displacement pump of cryogenic liquids which is relatively simple and inexpensive both in construction and operation.

Other objects and advantages of the present invention become apparent from the following detailed description when considered in conjunction with the accompanying drawings wherein:

FIGURE 1 is a cross sectional view illustrating a preferred embodiment of the pumping apparatus of the present invention;

FIGURE 2 is a cross sectional view taken generally along the line 2—2 in FIGURE 1;

FIGURE 3 is a cross sectional view taken generally along the line 3—3 in FIGURE 1; and

FIGURE 4 is a cross sectional view of the pumping apparatus taken generally along the line 4—4 in FIGURE 1.

In general, the present invention provides improved rotary positive displacement pumps (e.g. gear type, lobe type, vane type, etc.) for handling cryogenic liquids. In a preferred embodiment of the invention, a sealed housing is provided that defines an intake chamber, a pumping chamber, a passageway providing communication between the chambers, and intake and outlet ports communicating with the intake and pumping chambers, respectively. A first rotary positive displacement pumping

2

means is provided in the intake chamber so that successive portions of cryogenic liquid available at the intake port are delivered to and through the passageway to the pumping chamber by successively generated delivery compartments defined by this first rotary pumping means. A second rotary positive displacement pumping means is provided within the pumping chamber. Rotary motion imparted to the second rotary pumping means results in pumping and the continuous metered discharge of liquid from successively generated pumping compartments defined by the second rotary pumping means.

The structural arrangement of the pumping components is such that the first rotary positive displacement pumping means within the intake chamber does not perform any substantial amount of work but rather serves to deliver successive quantities of the cryogenic fluid from the intake port to the mouth of the passageway leading to the pumping chamber. Moreover, the second rotary positive displacement pumping means of the pumping stage is proportioned in relation to the pumping means of the intake stage so that a degree of controlled cavitation ("flashing") is realized as the fluid is continuously delivered from the intake chamber through the communicating passageway to the pumping chamber.

That is, each of the successively generated pumping compartments of the pumping stage has a greater volumetric capacity than do the corresponding and successively generated delivery compartments of the intake stage that supply liquid to the pumping compartment. The amount of the resulting cavitation ("flashing") is controlled so that the individual and successively generated pumping compartments, when communicating with the corresponding delivery compartments, each receive some vapor and some liquid. This condition is necessarily maintained so that the possibility of surging cavitation is eliminated (i.e. the intermittent delivery of pure vapor followed by pure liquid, etc.). The most certain means to assure this controlled cavitation results from proportioning the communicating passageway including the regions adjacent the inlet and outlet thereof with a volumetric capacity such that some liquid must pass into each successively generated pumping compartment of the second stage. That is, the volumetric capacity of this fluid conduit or passageway is selected so that it is preferably less than the volume of liquid delivered to it by the delivery compartments of the intake stage during the interval of time that one generated pumping compartment is positioned to receive liquid. However, it should be understood that in some applications the volumetric capacity of the communicating passageway might be equal to or slightly greater than the volume of the delivered liquid. The important factor is that some liquid be delivered into each successively generated pumping compartment of the second stage.

The manner in which rotary positive displacement pumps in accordance with the present invention achieve the efficient pumping of cryogenic fluids, absent vapor lock and without the need for auxiliary sub-cooling means, will be fully appreciated from a detailed consideration of the preferred embodiment illustrated in FIGURES 1—4. Although the present invention contemplates any of the various forms of rotary positive displacement pumps, the embodiment illustrated in the drawings and specifically described herein is a rotary gear type pump. Moreover, various structural details that would be obvious to one skilled in the art, that are subject to variation in different types of rotary pump constructions, and that do not form a part of the invention are not described in detail.

Referring in particular to the drawings, FIGURE 1

illustrates a rotary gear type positive displacement pump that includes an outer housing 10. The major portion of the housing 10 is formed by a pair of suitably proportioned outer casings 11 and 12 that are preferably formed of a material such as bronze or austenitic stainless steel. The casings 11 and 12 are mounted in sealing relationship on opposite sides of a central plate 13 by a plurality of suitable fasteners 14. The plate 13 is also preferably formed of bronze or austenitic stainless steel.

As shown, the upper casing 11 is provided with an intake port 16 that communicates with an intake chamber 17 which is defined by the casing 11 and the mating central plate 13. The intake chamber 17 serves as the housing for a pair of externally contacting spur gears 18, which are also preferably formed of a material such as bronze or austenitic stainless steel. More particularly, the intake chamber 17 formed in the casing 11 includes a pair of overlapping cylindrical chamber sections 19 (FIGURE 3), which are proportioned to receive the gears 18 in mating relationship while at the same time allowing the free and unrestricted rotation thereof as hereinafter described.

Similarly, the outer casing 12 in conjunction with the plate 13 defines a pumping chamber 21 which is comprised of a pair of overlapping cylindrical chamber sections 22. A pair of heliquid gears 23 are mounted for rotation within the chamber 21 in a manner similar to the mounting of the gears 18 within the chamber 17. As shown in FIGURE 2 the pumping chamber 21 communicates directly with an outlet port 25. The outer casings 11 and 12 are further provided with outwardly projecting generally cylindrical bearing housings 26 and 27, respectively. These outwardly projecting housings are preferably closed and sealed by end plates 28 and 29 so as to define enclosed housings for conventional self-lubricating bearing members 30 formed of materials such as polytetrafluoroethylene or polychlorotrifluoroethylene that are sold under the trademarks Teflon and Kel-F, respectively. The bearing members 30 are proportioned to receive the ends of shafts 31 and 32 whereon the gears 18 and 23 are mounted.

More particularly, the shaft 31 which is preferably driven by a conventional drive motor (not shown) extends into the housing 10 through a suitable packing structure 33 provided in the apertured portion of one of the end plates 28. As shown, this driven shaft has one of the coaxial spur gears 18 and one of the heliquid gears 23 keyed thereto (FIGURES 3 and 4) by keying members 34 and has the free end thereof positioned within a bearing member 30. The central portion of the shaft 31 confined within the housing extends through another self-lubricating bearing and sealing member 35 provided in an apertured portion of the central plate 13.

With the driven shaft so mounted, rotary motion imparted thereto results in the free and unrestricted rotation thereof thereby causing the gears 18 and 23 secured thereto to be similarly driven. The other of the gears 18, which is mounted on the shaft 32 and mates with the driven gear 18, is driven and caused to rotate thereby. Accordingly, the other of the gears 23, which is also keyed to the shaft 32, has rotary motion imparted thereto.

In this connection, the shaft 32 has the other of the gears 18 and 23 keyed thereto by keying members 34 and is suitably mounted for rotation within the end bearing members 30 and a central bearing and sealing member 35. The mounting of the shaft 32 and the gears secured thereto is, in a conventional manner, effected so that the gears 18 of the intake stage are maintained in close meshing relationship and actually contact so that rotary motion imparted to one of the gears causes the other to be similarly driven. Although the teeth of the driven heliquid gears 23 do not actually contact, these gears are mounted so that the clearance volume between the teeth thereof is minimized to preclude leakage. Moreover, the entire mounting of the gears, shafts and bearing members is such that

any void spaces within the chambers wherein cryogenic liquid might accumulate are substantially eliminated.

More particularly, the arrangement of the gears 18 and 23 and the mounting thereof within the chamber sections 19 and 22, respectively, is such that the free rotation of the gears is insured although the peripheral, upper and lower surfaces of each are closely fitted adjacent the chamber defining walls of the outer casings 11 and 12 and the central plate 13. Accordingly, during the rotation of the gears within the intake and pumping chambers, leakage between adjacent chambers and between successively generated delivery compartments 18a or pumping compartments 23a is essentially precluded.

As best seen in FIGURE 2, the central plate 13 is provided with a diagonally communicating passageway 36 that serves to link the intake chamber 17 to the pumping chamber 21. Accordingly, liquid delivered to the region in the intake chamber adjacent the mouth of the passageway 36 is delivered therethrough to the region in the pumping chamber adjacent the discharge end of the passageway. More particularly, successive portions of the liquid supplied at the inlet port 16 are delivered into and confined within the successively generated delivery compartments 18a. As the gears 18 are rotated in the direction of the arrows in FIGURE 3, these confined portions of the liquid are successively delivered to the region defined by the intake chamber defining surface of the central plate 13 and the peripheral portions of the gears 18. Thereafter, the fluid is circulated into and through the communicating passageway 36 and delivered to the region at the outlet of the passageway defined by the oppositely disposed pumping chamber defining surface of the plate 13 and the peripheral portions of the heliquid gears 23.

The relative size and fitting of the gears 18 and 23 and the dimensions of the passageway 36 are such that during the period that the individual pumping compartments 23a defined by the heliquid gears are positioned to receive liquid from the intake chamber some liquid and some vapor will be delivered thereto. This results from the interrelated structural and volumetric characteristics of the pump generally outline above.

More particularly, the heliquid gears 23 of the pumping stage, which are preferably formed of bronze or austenitic stainless steel, have dimensions such that volumetric capacity of the individual pumping compartments 23a generated during the rotation thereof is greater than that of the corresponding delivery compartments 18a generated within the intake stage as a result of the rotation of the mating gears 18. Accordingly, an amount of vaporization (i.e. flashing) occurs as the fluid expands into the individual pumping compartments 23a from the corresponding delivery compartments 18a.

By controlling this volumetric capacity differential between the delivery compartments 18a and the pumping compartments 23a, the degree of flashing can also be controlled so that some liquid and some vapor is continuously discharged into the communicating passageway.

In addition, the communicating passageway including the regions adjacent the inlet and outlet ends of the passageway is dimensioned so that a portion of the liquid delivered thereto during any selected interval when a single pumping compartment 23a is positioned to receive fluid is necessarily transferred to this pumping compartment. Consequently, each of the successively generated pumping compartments are continuously and assuredly supplied with some liquid that is conveyed to the outlet port 25, compressed and discharged to the high pressure portion of the system. This conveyance is carried out as the heliquid gears 23 are driven in the direction of the arrows in FIGURE 4. As previously pointed out, the transfer of some liquid to each pumping compartment 23a is preferably assured by forming the passageway 36 with a volumetric capacity less than the volume of liquid that might be delivered thereto when a pumping compartment is positioned to receive the liquid. However, a passageway

having a volumetric capacity equal to or slightly greater than the volume of liquid that might be delivered may be employed in some applications.

The novel structural configuration of the pump, as described above, leads to essentially vapor lock free operation and yields relatively efficient pumping of cryogenic liquids. Moreover, the gears 18 of the intake stage act essentially as delivery members and perform a minimal amount of work inasmuch as the liquid delivered thereby from the inlet port to the communicating passageway is essentially passing from a higher pressure to a lower pressure region. This advantage, which stems from the volumetric capacity differential between the generated delivery compartments 18a and pumping compartments 23a that are supplied thereby, necessarily results in less heat input to the liquid as it is transferred from the inlet port to the communicating passageway 36.

Moreover, flashing of the liquid occurs as the delivery compartments 18a discharge their contents at the inlet to the communicating passageway 36 and the decrease in temperature accompanying this flashing results in some cooling of the gears 18. Accordingly, the possibility of vaporization of the incoming liquid at the inlet port as a result of heating is eliminated. An additional advantage of the pump construction, as described above, stems from the larger volumetric capacity of the generated pumping compartments 23a. That is, the amount of leakage that occurs per volume of liquid pumped by each of these generated pumping compartments is reduced. Accordingly, heat pickup, which is incidental to the friction created by the leakage of fluid from the generated pumping compartments 23a around the peripheral and end sections of the heliquid gear teeth, is minimized.

One specific embodiment of a gear type pump embodying the structural features as previously described has a pumping capacity of 3 gallons a minute when transporting oxygen at a temperature of -292° F. from an inlet port having a pressure of 5 p.s.i.g. to an outlet port having a pressure of 500 p.s.i.g. To accomplish this, the gears 18 preferably have a radius of 1 inch, a thickness of 1 inch, and each successively generated delivery compartment 18a (13 per gear) is capable of delivering 0.045 cubic inch of cryogenic fluid. The passageway 36 preferably has a capacity of less than approximately 0.14 cubic inch. Moreover, the gears 23, which are preferably heliquid gears, are selected to have a pumping capacity of 6 gallons per minute. The gears 18 and 23 are driven by a motor so that a rotational velocity of 600 revolutions per minute is realized.

It should be understood that modifications of various of the structural and functional features of the illustrated embodiment of the pump would be obvious to those skilled in the art and would not depart from the invention, various features of which are set forth in the following claims.

What is claimed is:

1. A pump for handling cryogenic liquids which comprises a housing that defines an intake chamber having an intake port communicating therewith, a pumping chamber having an outlet port communicating therewith, and a passageway providing communication between said chambers; a first rotary positive displacement pumping means mounted within said intake chamber so that rotary motion imparted thereto results in the successive generation of delivery compartments by said first pumping means that are advanced from said inlet port to the inlet of said passageway; a second rotary positive displacement pumping means mounted within said pumping chamber so that rotary motion imparted thereto results in the successive generation of pumping compartments by said second pumping means that are advanced from the outlet of said passageway to said outlet port; and means synchronizing the rotary motion of said first and second pumping means so that successive ones of said pumping compartments transiently communicate with at least one of said suc-

sively generated delivery compartments through said passageway, each of said pumping compartments having a volumetric capacity greater than the volumetric capacity of the corresponding delivery compartments transiently communicating therewith and said communicating passageway having a volumetric capacity such that some liquid is supplied from the successively generated delivery compartments to said successively generated pumping compartments that transiently communicate therewith.

- 5 2. A device for pumping cryogenic liquids from a low pressure portion of a system to a higher pressure portion of the system, which device comprises a housing that defines an intake chamber having an intake port communicating therewith and with the liquid supplied from the system, 10 a pumping chamber having an outlet port communicating therewith and with the higher pressure portion of the system, and a passageway providing communication between said chambers; a first pair of positive displacement rotary pumping members mounted within said intake chamber so that rotary motion imparted thereto results in the successive generation of delivery compartments by said first pair of pumping members that deliver quantities of the liquid from said inlet port to the inlet of said passageway; a second pair of positive displacement 15 rotary pumping members mounted within said pumping chamber so that rotary motion imparted thereto results in the successive generation of pumping compartments by said second pair of pumping members that pump successive portions of the delivered liquid from the outlet of said passageway to said outlet port; and means synchronizing the rotary motion of said first and second pairs of pumping members so that successive ones of said pumping compartments transiently communicate with at least one of said successively generated delivery compartments through 20 said passageway; each of said pumping compartments having a volumetric capacity greater than the volumetric capacity of the corresponding delivery compartments transiently communicating therewith and said communicating passageway having a volumetric capacity less than the volumetric capacity of the successively generated delivery compartments that communicate through said passageway with one of said successively generated pumping compartments.

- 25 3. A pump for handling cryogenic liquids which comprises a housing that defines an intake chamber having an intake port communicating therewith, a pumping chamber having an outlet port communicating therewith, and a passageway providing communication between said chambers; a first pair of driven mating gear members mounted 30 within said intake chamber so that rotary motion imparted thereto relative to the intake chamber defining walls of said housing results in the successive generation of delivery compartments by the teeth thereof that are advanced from said inlet port to the inlet of said passageway; a second pair of driven mating gear members mounted within said pumping chamber so that rotary motion imparted thereto relative to the pumping chamber defining walls of said housing results in the successive generation of pumping compartments by the teeth thereof that are advanced from the outlet of said passageway to said outlet port; and means synchronizing the rotary motion of said first and second pairs of driven mating gear members so that successive ones of said pumping compartments transiently communicate with at least one of said successively generated delivery compartments through said passageway, each of said pumping compartments having a volumetric capacity greater than the volumetric capacity of the corresponding delivery compartments transiently communicating therewith and said communicating passageway having a volumetric capacity such that some liquid is supplied from the successively generated delivery compartments to said successively generated pumping compartments that transiently communicate therewith.

- 35 4. A device for pumping cryogenic liquids from a low

pressure portion of a system to a higher pressure portion of the system, which device comprises a housing that defines an intake chamber having an intake port communicating therewith and with the liquid supplied from the low pressure portion of the system, a pumping chamber having an outlet port communicating therewith and with the higher pressure portion of the system, and a passageway providing communication between said chambers; a first pair of driven mating gear members mounted within said intake chamber in driving contact with each other so that rotary motion imparted to one of said pair results in the other of said pair being driven thereby, the teeth of said driven mating gear members effecting the successive generation of delivery compartments as said gear members are rotated from said inlet port to the inlet of said passageway and relative to the intake chamber defining walls of said housing, a pair of heliquid gear members mounted in close meshing but non-contacting relationship within said pumping chamber, the teeth of said heliquid gear members effecting the successive generation of pumping compartments as said gears are advanced

5

10

15

20

from the outlet of said passageway to said outlet port and relative to the pumping chamber defining walls of said housing; and means connecting one of said pair of driven gear members to one of said heliquid gear members and the other of said pair of driven gear members to the other of said heliquid gear members so that rotary motion is imparted to said heliquid gear members which is synchronized with the rotary motion of said driven gear members whereby successive ones of said generated pumping compartments transiently communicate with at least one of said successively generated delivery compartments through said communicating passageway; each of said pumping compartments having a volumetric capacity greater than the volumetric capacity of the corresponding delivery compartments transiently communicating therewith and said communicating passageway having a volumetric capacity less than the volumetric capacity of the successively generated delivery compartments that communicate through said passageway with one of said successively generated pumping compartments.
